BIT

Earl A. Reed, Garber, Okla.

Application September 28, 1931
Serial No. 565,595

9 Claims. (Cl. 255—71)

My invention relates to deep well drilling apparatus and more particularly to improvements in drill bits such as shown in my application, Serial No. 194,315, filed May 26, 1927.

5 One object of my invention is to provide a drill bit roller cutter and bushing in a unitary assembly which may be easily and securely mounted upon the supporting spindle of a drill head and detached therefrom.

10 Another object of the invention is to prevent slipping and chattering of the bushing upon the supporting spindle and the entrance of grit and water therebetween and into the lubricating channels so as to minimize weaving of the bearing surfaces of the device.

15 Another object of the invention is to prevent the abrasive bearing circulating fluid, which is forced through the drill head, from forming eddies adjacent thereto, which would normally 20 wear away portions of the drill head.

25 A further object is to provide means for insuring adequate lubrication of the bearing surfaces of the roller cutter and bushing, particularly at the portions of their greatest diameter and relative speed.

30 A still further object of the invention is to provide a method of making the roller cutter and bushing assembly such that a unitary bushing is formed partially inside a bearing cavity of the cutter so that all wear due to the rotation of the cutter takes place between the bushing and cutter and that chance separation of the cutter and bushing is prevented.

35 Other objects and advantages of the invention will appear in the following description of the preferred embodiment of the invention shown in the attached drawings of which:

Fig. 1 is a front elevation of a drill head assembly partly in section;

40 Fig. 2 is a side elevation thereof;

Fig. 3 is a bottom view of the drill head with the cutter assemblies removed;

Fig. 4 is a plan view of the cutter bushing partly broken away; and

45 Fig. 5 is a sectional view of a modification of the device.

Referring more particularly to the drawings, 50 10 represents the body portion of the drill head assembly. As shown in Fig. 3 the body portion is circular in horizontal cross section with flattened sides 11. The upper portion 12 of the body is smaller in diameter and is provided with tapering threads 13 for attachment to a hollow drill pipe (not shown). In the 55 modification shown in Figs. 1 to 4, the body is

provided with depending legs 14 which terminate in substantially conical spindles 15 which are adapted to receive a cutter and bushing assembly indicated generally by 16.

Each cutter and bushing assembly 16 consists of a roller cutter 17 and a hardened steel internal bushing 18. The cutter 17 has a substantially conical outer surface which is provided with a plurality of cutting teeth 19. Each cutter 17 is provided with an internal frusto-conical bearing cavity 20, diametrical elements of which are at right angles to each other. Near the base of the cutter the cavity is provided with an internal flange 21. The surface 22 of said flange, which is remote from the base of the cutter, is also frusto-conical and its diametrical elements are at less than a right angle to each other with their apex upon the same central axis as the apex of the elements of the bearing cavity 20 but oppositely disposed. The surface 23 of said flange adjacent the base of the cutter is frusto-conical and has its elements parallel to corresponding elements of the bearing cavity 20.

50 In its finished form the bushing 18 is an integral member having an outer bearing surface conforming to and fitting the inner bearing surface of the roller cutter, and is provided with an external groove having frusto-conical surfaces to receive the internal flange 21 of the cutter. The bushing is provided with an internal substantially conical cavity 25 which receives the conical spindle 15 of the drill head.

55 Before insertion into the bearing cavity 20, the bushing consists of a plurality of sections. The bushing is preferably diametrically divided into two oppositely disposed major sections 26 and 27, and two smaller sections 28. As clearly shown at 29 in Fig. 4, wherein one of the smaller sections 28 has been shown as partially broken away, the abutting edges of the respective sections are inclined or beveled such that a smaller section 28 may be easily inserted 100 in the bearing cavity 20 after the other sections of the bushing have been inserted therein. Also as shown at 30 the inner portions of abutting edges are cut away, as at 30, to form grooves 31 when the bushing is assembled. After insertion in the bearing cavity 20 these grooves are filled with molten metal which fuses with the bushing sections, preferably by an electric welding operation. The inner cavity 25 of the bushing is then finished to give a smooth conical surface 105 fitting the spindle 15.

- The diametrical elements of the spindle surface form right angles with each other and the axes of the spindles are positioned at an angle of 45° with the axis of the drill head body 10. The base of the bushing 18 makes an angle of 45° with the axes of the drill head body and said base is provided with a flat circular surface 32. The surface 33 of the depending legs 14 of the drill head, which surrounds the spindles 15, is finished to a flat plane inclined 45° to the axis of the drill head to receive the base surface 32 of the bushing. As shown on Figs. 1 and 3 the depending legs 14 are provided with radially protruding portions 34, the lower surface of which forms a continuation of the inclined plane surface 33. The bushing 18 has formed in its inner surface a recess 35 to receive a retaining member 36 which is screw threaded into a recess 37 formed in the lower surface of the spindle 15. Also formed in the inner surface of the bushing and diametrically opposite the recess 35 is a second recess 38 provided with screw threads 39 to receive the threaded end of a fastening element 40 which extends through a transverse bore 41 in the leg 14. The fastening element 40 is provided with a head 42 which is received in a recess 42a, concentric with the bore 41 and a washer 43 is positioned under the head of the fastening element 40. The bore 41 is provided with an internal annular groove 44 which is connected with an oil duct formed in the drill head and extends from the extreme upper end thereof. The upper end of drill head is provided with screw threads 46, forming attaching means for a lubricator (not shown). Transverse holes in the fastening element 40 register with the annular groove 44 and an axial bore 48 in the fastening element intersects said transverse holes. Said axial bore registers with a hole 49 extending through the bushing from the bottom of the recess 38, and concentric therewith, to provide an oil duct leading to the bearing surfaces of the bushing at a point near their outer periphery and greatest relative speed. Another bore 50 extending axially of the spindle 15 intersects the annular groove 44 and registers with an axial bore 51 in the bushing to form an oil duct to the central bearing surfaces of the bushing and cutter. The inner surface of the cutter is recessed at 52 to form a circular cavity adjacent the truncated portion of the bushing to provide a passage for the oil to the inner conical bearing surfaces.
- In the device shown in Fig. 5 a modified form of bushing and cutter assembly 16' is carried by a conical spindle 15' formed upon the lower end of each leg 14' depending from the body portion 10 of the drill head assembly. As in the previously described modification, the cutter 17' is provided with cutting teeth 19 and is carried by a bushing 18'. The cutter has an internal frusto-conical bearing cavity 20' provided with an internal flange 21', having a surface 22 remote from the base of the cutter which is frusto-conical and similar to the surface 22 of the previously described modification. The flange also has a surface 23' which is frusto-conical and has its elements parallel to corresponding elements of the bearing cavity 20'. In addition the flange has a surface 23a which is perpendicular to the axis of the cutter and is adapted to abut an annular flange 18a forming the base of the bushing 18'. The bushing 18' is an integral member formed of sections which are welded together and finished after their insertion into the bearing cavity of the cutter 17' in the same manner as the bushing 18 described above and has an outer bearing surface fitting and conforming to the inner bearing surface of the cutter. The flange 18a has a base surface 18b adapted to fit against an annular plane surface 33' upon the leg 14' surrounding the spindle 15' and inclined at an angle of 45° to the axis of the drill head. By this structure the entrance of abrasive and water and loss of lubricant is practically prevented. The weight of the operating member and drill head presses the flat surface of the flange 18a against the flat base 23a of the roller cutter during operation thereof, to form an effective seal.
- The bushing and cutter assembly 16' is retained upon the spindle 15' by means of retaining member 36 and locking member 40 as in the previously described modification and the spindle 15', bushing 20' and locking member 40 are provided with lubricating ducts 48, 49, 50, and 51, as in that modification.
- The bore 41' through which the locking element 40 is inserted is enlarged at its upper portion so that, in the event the spindle 15' becomes worn or an accurate fit between the bushing 18' and spindle 15' is not obtained in the field, shocks received by the cutter and bushing assembly will not be sustained by the locking element 40 but will be transmitted to the spindle 15'.
- The body portion of the drill head is also provided with a longitudinally extending bore 53 through which abrasive bearing water is forced. Inclined holes 54 extend from the upper end of said bore to the exterior of the body portion and inside the drill pipe (not shown). The lower end of the bore is enlarged and internally threaded to receive a detachable externally threaded nozzle 55 which is threaded into said bore. The nozzle is provided with a converging bore 56 concentric with the bore 53 and of the same diameter at its larger end. The nozzle is further provided with a cylindrical discharge bore 57 concentric with the bore 53 and of smaller diameter. The form of nozzle shown delivers the circulating fluid in a straight even stream, which does not form eddies adjacent the drill head which would rapidly wear said head, due to the abrasive in the liquid. The straight downwardly directed stream is also effective to wash the cutter and remove material adhering between the teeth thereof.
- In the use of drilling apparatus having rotary cutters, it is necessary to frequently provide the drill head with new cutters, as the cutting teeth and bearing surfaces become worn. It will be noted that the cutters and bushings herein described are adapted to be furnished to drillers as unitary assemblies wherein an integral bushing is retained in the cutter by an internal flange so that chance separation of the cutter and bushing is prevented before installation on the drill head or after such installation and during the drilling operation. The cutter and bushing assembly may be placed and securely retained upon the spindle by merely slipping it axially of the drill head over the conical spindle and tightening the single fastening element 40. The flat base of the bushing fits snugly against the inclined plane on the drill head, effectually preventing any of the abrasive carrying circulating

liquid penetrating between the drill head and bushing and into the lubricating channels. The bushing is held firmly and non-rotatably against the spindle by the fastening element 40 and the retaining member 36 such that slipping and chattering of the single piece bushing upon the spindle is prevented. Since the spindle is usually formed of cast steel and is of softer metal than the hardened steel bushing, I have discovered means to greatly lengthen the useful life of the spindle by applying a hard surfacing material such as Stellite, or the like to the surface of said spindle. All wear due to the rotation of the cutters takes place between the renewable bushing and cutter, and the portion of the bushing adjacent the base thereof forms an effective wear plate integral with the bushing, for preventing contact between the cutter and drill head.

It will also be noted that the fastening element 40 serves as a means for supplying lubricant to the wearing surfaces adjacent the periphery thereof whereby centrifugal force, due to the rapid rotation of the cutter, causes the lubricant to flow outwardly, insuring an adequate supply at the outer edges. The cavity 52 at the center of the cutter allows the lubricant to readily flow an appreciable distance from the axis thereof such that centrifugal force is effective to cause the adequate lubrication of the more central portions of the wearing surfaces.

I claim as my invention:

1. The combination with a roller boring drill head, of a duct adapted to permit passage of lubricant downwardly from a lubricant container to be connected adjacent the top of said drill head to an annular groove in a lateral bore through a spindle of said drill head, a cutter assembly locking plug disposed within said bore, inlet ducts for passage of lubricant diametrically through said locking plug and registering with said annular groove, an outlet duct for passage of lubricant extending centrally from the inner end of said locking plug to and intersecting said diametrical ducts therein, a duct for the passage of lubricant through a bushing registering with the outlet of said outlet duct, and a second lubricant course comprising registering ducts leading from said annular groove in said lateral bore to the interior of a frusto-conical roller cutter adjacent its truncated apex through said spindle and bushing.

2. In a roller boring drill, the combination with a drill head having a downwardly extending frusto-conical cutter supporting spindle, of a roller cutter assembly adapted to be associated with and supported by said spindle, said cutter assembly comprising relatively rotatable cutter and bushing elements, the latter having an interior frusto-conical surface substantially matching the frusto-conical surface of the spindle, and a locking element secured to said spindle and extending outwardly from the frusto-conical surface thereof, said bushing element having a recess adapted to receive said locking element, and a second locking element removably associated with said spindle and adapted to be screw threaded into a second recess in said bushing element.

3. The combination with a roller boring drill head having a spindle and a duct adapted to permit passage of lubricant downwardly from the top of said drill head to a lateral bore through the spindle of said drill head, a cutter assembly locking plug disposed within said bore

and having an inlet duct for passage of lubricant diametrically into said locking plug and an outlet duct for passage of lubricant extending from the inner end of said locking plug to and intersecting said diametrical duct, a bushing mounted upon said spindle and having a duct registering with said outlet duct for the passage of lubricant through the bushing to the bearing surface thereof.

4. The combination with a roller boring drill head having a spindle and a duct adapted to permit passage of lubricant downwardly from the top of said drill head to a lateral bore through said spindle, a cutter assembly locking plug disposed within said bore and having an inlet duct for passage of lubricant diametrically through said locking plug, said locking plug having an outlet duct extending from the inner end of said locking plug to and intersecting said diametrical duct for passage of lubricant, a frusto-conical bushing mounted upon said spindle and having a duct registering with said outlet duct for the passage of lubricant to the surface of said bushing, said spindle and said bushing having registering ducts leading from said lateral bore to the surface of said bushing adjacent its truncated apex.

5. In a roller boring drill, the combination of a drill head having a cutter supporting spindle, a roller cutter assembly supported upon said spindle, said cutter assembly comprising relatively rotatable cutter and bushing elements, said spindle having a bore extending therethrough, a screw plug positioned in said bore and having screw-threaded engagement at its inner end with said bushing for locking said bushing in non-rotatable position, said bore being of greater diameter than said screw plug, said screw plug having a longitudinal duct extending from its screw-threaded end and a transverse duct connecting said longitudinal duct with said bore, said drill head having a duct for supplying lubricant to said bore.

6. In a roller boring drill, the combination of a drill head having a cutter supporting spindle, a roller cutter journaled upon said spindle, said spindle having a transverse bore extending therethrough, a screw plug positioned in said bore and having its inner end terminating adjacent the inner surface of said cutter, said screw plug having a portion within said bore of smaller diameter than said bore, said screw plug having a duct extending longitudinally from its inner end for at least a portion of its length and also having a transverse duct intermediate its ends, connecting said longitudinal duct and the transverse bore of said spindle, said drill head having a duct adapted to supply lubricant to said transverse bore.

7. In a roller boring drill, the combination of a drill head having a cutter supporting spindle, a bushing non-rotatably mounted upon said spindle, said bushing having a conical outer bearing surface, a conical roller cutter having a conical inner bearing surface positioned upon said bushing for rotation relative thereto, a locking member positioned in a bore in said spindle and having its inner end terminating adjacent the periphery of the bearing surface of said bushing, said member having a duct extending from its inner end and connecting with a source of lubricant for transmitting lubricant to the outer portion of the bearing surface of said bushing.

8. In a roller boring drill, the combination of

a drill head having a cutter supporting spindle, a bushing non-rotatably mounted upon said spindle, said bushing having a conical outer bearing surface, a conical roller cutter having a conical inner bearing surface positioned upon said bushing for rotation relative thereto, a screw plug positioned in a bore in said spindle and having its inner end terminating adjacent the periphery of the bearing surface of said bushing, said screw plug having a longitudinal duct extending from its inner end and a transverse duct connecting said longitudinal duct with a source of lubricant to transmit lubricant to the outer portion of the bearing surface of said bushing.

5. The combination with a roller boring drill head, of a pair of downwardly projecting legs, frusto-conical spindles formed on said projecting legs whose axis are inclined downwardly and inwardly, a locking element projecting downwardly from the surface of each of said spindles, each of said spindles being provided with a lateral aperture, a removable locking element carried in each said lateral aperture, one end of which projects beyond the inner surface of each said spindles when in operative position, a frusto-conical roller cutter for each said spindles mounted upon a frusto-conical bushing, said bushing having frusto-conical 8
socket fitting said frusto-conical spindle and retained thereon by coaction of said locking elements with recesses in said bushing, said lateral aperture being enlarged above said removable locking element to permit upward movement of 90
said removable locking device due to wearing of 95
said bushing and spindle.
